UNITED STATES PATENT OFFICE.

CHARLES G. TROSIEN, OF PONTIAC, MICHIGAN.

GEAR-LOCK FOR AUTOMOBILES.

1,366,299.

Specification of Letters Patent. Patented Jan. 18, 1921.

Application filed August 16, 1919. Serial No. 317,856.

To all whom it may concern:

Be it known that I, CHARLES G. TROSIEN, a citizen of the United States, residing at Pontiac, county of Oakland, State of Michigan, have invented a certain new and useful Improvement in Gear-Locks for Automobiles, and declare the following to be a full, clear, and exact description of the same, such as will enable others skilled in the art to which it pertains to make and use the same, reference being had to the accompanying drawings, which form a part of this specification.

My invention relates to gear locks for automobiles and an object of my improvements is to provide an improved gear lock to be used with the construction of a Ford automobile.

In the accompanying drawings:

Figure 1 is a plan view of the housing for the change speed gearing in a Ford automobile.

Fig. 2 is a side elevation of the same partly broken away.

Fig. 3 is a detail view of a part of the interior construction partly in section.

Fig. 4 is a detail inverted plan view of the lower end of the locking cam rod.

Fig. 5 is a detail side elevation of the mechanism shown in Fig. 3 and adjacent parts, partly broken away to show the interior construction.

Fig. 6 is a view similar to Fig. 5 the cam rod being in a different position.

Fig. 7 is a plan view of a portion of the housing, a modified form of construction embodying my invention being shown.

Fig. 8 is a section on the line VIII—VIII, Fig. 7.

Fig. 9 is a view similar to Fig. 8 showing the parts in a different position.

Fig. 10 is a detail section taken on the line X—X, Fig. 9.

Fig. 11 is an end view of the locking sleeve detached from the assembly.

Fig. 12 is a plan view of the casing with a third modification of mechanism embodying my invention.

Fig. 13 is a detail sectional elevation of the same.

Fig. 14 is a section on the line XIV—XIV, Fig. 13.

Fig. 15 is a detail view showing the ad-

jacent faces of the locking sleeve and lug shown.

Fig. 16 is a modified construction of the form shown in Figs. 7 to 11, inclusive.

⁵⁵
a is the housing for the change speed gearing, b is the transverse rock shaft, bearing in said housing and carrying the striker levers b^1 , b^2 . Upon the hubs of said levers extending upward I form adjacent lugs b^3 , b^4 . c is a socket secured or formed in the cover of the casing a extending vertically with its axis in the plane of the rock shaft b, its lower end coming just above the lugs b^3 , b^4 . c^2 is a cylindrical piece, or rod, having cams c^3 , c^4 on its lower end. The cam rod c^2 fits and is adapted to rotate in the lower end of the socket c and extends ⁶⁰ downward therefrom so that its cams c^3 , c^4 come in the plane of the lugs b^3 , b^4 . When the rod c^2 is turned to the position shown in Fig. 5 the cams c^3 , c^4 come in the line of travel of the lugs b^3 , b^4 and the rod b is ⁶⁵ therefore locked and restrained from turning. When the cam rod c^2 is turned at right angles to the position shown in Fig. 5, that is, to the position indicated in Fig. 6, the lugs c^3 come at the side of the lugs b^3 and ⁷⁰ are not in the line of travel of the latter so that the rod b is free to turn or rock in its bearing. c^4 is a spindle extending upward from the cam rod c^2 and connected at its end with the barrel of a pin-lock c^5 which ⁷⁵ may be operated by a key c^6 .

In the form shown in Figs. 7 to 11, inclusive, socket pieces c is replaced by a similar construction ca, cast in the side of the housing a. In this form the cam rod c^2 ⁸⁰ has a single eccentric cam c^3a extending from its lower end and the socket piece ca is provided with an inwardly opening transverse aperture c^6 . b^2a is a sleeve pinned or keyed upon the shaft with its face ⁸⁵ adjacent to a corresponding face formed at the interior of the socket piece ca. b^3a is an aperture formed in the face of the sleeve b^2a so that when the rock shaft b is in its normal position said aperture shall be axially in line with the aperture c^6 with the socket piece ca. e is a ball in the apertures c^6 , b^3a . When the rock shaft b is unlocked, as shown in Fig. 9 the cam rod c^2 is turned ⁹⁰ to the position shown in the last-named ⁹⁵ figure, so that the ball e is free to move

- entirely into the aperture in the socket piece c^a , and the sleeve b^2a , will turn freely. When the cam rod c^2 is turned to the position shown in Fig. 8, the cam c^3a thrusts 5 the ball e partly out of the aperture c^3 so that it shall engage in both of the apertures b^3a and c^6 so that the sleeve b^2a and consequently the rod b is locked to prevent a rocking motion.
- 10 Instead of the arrangement just described in which the ball e engages in two cavities, one of which is in a stationary part and the other located eccentrically in a part connected to the rod b , a vertically reciprocating rod c^2a (Fig. 16) may be used, which, at the lower end of its travel engages in two 15 apertures b^3a^2 and c^6a , one of which is stationary and the other eccentrically located in the rod b .
- 20 In the forms shown in Figs. 12 to 15 inclusive, there is a sleeve g keyed upon the shaft b so as to restrain it from relative angular motion but permitting of motion longitudinally of the shaft b . This is provided with a transverse slot g^2 at its upper 25 portion and with two lugs g^3 at opposite points of its periphery. There is a lug f formed opposite the sleeve g upon the wall of the casing a and in this lug are formed 30 slots or apertures f^2 corresponding to the lug g^3 on the sleeve g . There is a cam rod c^2 having an eccentric lug c^3a thereon which engages in the slot g^2 . When the rod c^2 is turned to one position the sleeve g is 35 moved by a compression spring h to its position farthest to the left, as shown in Fig. 15, and the lugs g^3 are entirely clear of the slots f^2 . When the rod c^2 is turned the cam c^3a engages a wall on the slot g^2 forcing 40 the sleeve g to the right and engaging the lugs g^3 in the slots f^2 and the rock shaft b is locked from angular motion.

What I claim is:

1. In an apparatus of the kind described, 45 a transmission gear casing, a transmission gearing in said casing, a rock shaft inclosed in said casing and forming a part of the transmission gearing, a part adjustable at will extending through said casing and

adapted to engage said rock shaft and disengage the same and means for locking said part in its engaged position.

2. In an apparatus of the kind described, a transmission gear casing, a transmission gearing in said casing, a rock shaft inclosed in said casing and forming a part of the transmission gearing, a movable part 55 engaging a stationary support, and means adjustable at will extending through said casing and adapted to actuate said movable part to engage said rock shaft at a point eccentric thereto or to disengage said movable part, and a lock for securing said means in the position at which it causes said engagement.

3. In an apparatus of the kind described, a transmission gear casing, a transmission gearing in said casing, a rock shaft inclosed in said casing and forming a part of the transmission gearing, said shaft being supplied with an eccentric slot in a part, a stationary part provided with a slot axially in line with the first-mentioned slot, a part adapted to reciprocate in said slot and a rod extending through said casing 70 adapted to actuate said reciprocating part to cause it to engage in both of said slots or to engage solely in one of said slots and a lock for preventing the movement of said rod.

4. In an apparatus of the kind described, a transmission gear casing, a transmission gearing in said casing, a rock shaft inclosed in said casing and forming a part of the transmission gearing, a sleeve upon 85 said rod rigidly secured thereto, said sleeve being provided with an aperture in its side face, a stationary part provided with an aperture in line with and forming an extension of the first-mentioned aperture, a ball 90 adapted to reciprocate in said apertures, and a rotatable rod extending through said casing adapted to actuate said ball for the purpose described and means for locking said rotatable rod.

95 In testimony whereof, I sign this specification.

CHARLES G. TROSIEN.
